UNITED STATES PATENT OFFICE.

DAVID DICK, OF MEADVILLE, PENNSYLVANIA.

IMPROVED PROCESS OF BURNING PETROLEUM AND OTHER LIQUID FUEL FOR THE GENERATION OF STEAM AND FOR OTHER PURPOSES.

Specification forming part of Letters Patent No. 38,732, dated June 2, 1863; antedated April 28, 1863.

To all whom it may concern:

Be it known that I, DAVID DICK, of Meadville, in the county of Crawford and State of Pennsylvania, have invented or discovered a certain new and useful method of using mineral oils as fuel for generating steam and for other purposes, of which the following is a full, clear, and exact description, reference being had to the accompanying drawings, which make part of this specification, and in which—

Figure 1 represents a view in perspective of so much of a mineral-oil furnace embracing my improvements as is necessary to illustrate my invention, and Fig. 2 a vertical section through the same at the line xx of Fig. 1.

My invention has for its object a novel method of employing mineral oils as fuel for the generation of steam and for other analogous purposes.

To this end the improvement claimed under this patent consists in saturating a bed, stratum, or layer of some material, either incombustible or refractory to heat, with oil, and igniting it upon the surface thereof, by which method the oil is prevented from being dashed about by the motion of the furnace, and the danger of too rapid an ignition or of an explosion is prevented.

To carry out the object of my invention in the best manner, I substitute for the furnace and grate heretofore used with solid fuel a water or oil tight vessel filled with some incombustible or refractory material, either porous in its structure or else broken into lumps. This material is saturated with oil, and is ignited upon its surface, air to support combustion being supplied in proper quantity and in any suitable or convenient manner.

In the accompanying drawings, which exemplify one mode of carrying out the object of my invention, the furnace is shown as consisting of a water tight rectangular metallic casing or water-box, A, within which a similar box, B, of smaller size is placed, the space between the two forming a chamber, C, which is kept full of water to prevent the fire-box B from being overheated. The water in this instance enters the chamber through one, a , of the pipes, and flows out at the other. In cases where the furnace is liable to agitation—as in locomotive or marine engines—the water-

chamber C should be tightly closed to prevent the spilling of the water. Air is supplied to the flame in this instance through flues D, passing up through the bottom of the furnace. For convenience of construction, the two boxes A and B may be made separately, as shown in Fig. 2; but in such cases the joint which connects them should be perfectly tight. The space around the air-flues D is filled with some porous incombustible or refractory material, E. Ashes, sand, gravel, bricks, crushed pottery, asbestos, magnesia, pumice-stone, and other materials of like nature may be used for this purpose, but my experiments lead me to prefer pumice-stone. This may be used in solid blocks to advantage, but I prefer to use it crushed into small lumps, about the size of a pea. The oil, in this instance, enters the fire-box through a supplying-pipe, F, provided with a stop-cock, G, to regulate its flow. It may, under some circumstances, require to be forced in by a pump; but if the tank be situated above the level of the fire-box the hydrostatic pressure alone will generally be sufficient for this purpose. As the oil enters the fire-box, it percolates through the porous material, which allows it to pass freely, and yet prevents it from dashing about and being spilt over the edges of the furnace, which, in locomotive and marine engines, is of essential importance. The oil, when ignited, burns freely upon the surface of the porous material, while the water by which the fire-chamber is surrounded prevents the furnace from becoming heated and generating gas in the bottom of the fire-box, which might, under certain conditions, be dangerous.

In order to extinguish the flame when desired, I employ an extinguisher-plate, H, (shown in red lines in Fig. 1 and in blue section-lines in Fig. 2, as constructed to slide over the top of the furnace and cut off the supply of air by closing the flues D.) As the heat of the furnace would cause the generation of gas from the oil for some time after the flame was extinguished, I make a series of small holes, h , Fig. 1, in the extinguisher-plate H, of a sufficient size for the escape of gas, but too minute for the passage of the flame; otherwise the gas might force off the plate.

The advantages attained by my invention

are so obvious, especially as adapted to marine or locomotive engines, where weight and bulk are such paramount considerations, as scarcely to require notice. The heating-powers of the oils proposed to be employed are so great that at the prices at which they are now sold the cost of running an engine with this kind of fuel would scarcely exceed that of coal, if at all, and would be far cheaper than wood. From data derived from my experiments, I estimate that one of the Collins' steamers could be driven across the Atlantic by the consumption of about two hundred tons of oil, which would occupy far less space than the quantity of coal required for the same purpose, and the greater cargo-space thus obtained would more than compensate for any enhanced cost of fuel. It is, moreover, but the work of an instant to light or extinguish the fires, while under the old plan much time and fuel were necessarily consumed in this way. The mere turning of the cock which regulates the flow of oil gives complete control over the intensity of the flame, and consequently the amount of steam generated. The tanks might be made to conform to the shape of a vessel and the oil serve as ballast, its place being supplied by water as the oil was expended. The pressure of the water upon the sides of the ship might even be used to force the oil into the furnace, as from its lighter

specific gravity it would always float upon the water, and thus an automatic feed be secured, even with the tanks below the level of the furnace.

My invention might likewise be adapted to cooking, heating, and other analogous purposes with but little, if any, modification of the plan shown. I do not, therefore, limit myself to the combination and arrangement hereinbefore shown and described, for it is obvious that they may be modified in various ways without departing from the spirit of my invention, and such modifications would readily occur to a skillful mechanic after reading my specification.

What I claim as my invention, and desire to secure by Letters Patent, is—

The method of employing coal-oil, petroleum, or other mineral oils as fuel for the generation of steam, or for other purposes, by saturating a bed or stratum of incombustible or refractory materials with the oil, and burning it upon the surface thereof, substantially in the manner described.

In testimony whereof I have hereunto subscribed my name.

DAVID DICK.
